UNITED STATES PATENT OFFICE

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

CENTRALIZER FOR DRILL STEELS

Application filed June 23, 1928. Serial No. 287,766.

This invention relates to rock drills, but more particularly to a centralizer for the working implement, such as a drill steel adapted to be actuated by rock drills of the 5 hammer type.

One object of the invention is to guide and support the overhanging portion of the drill steel so that in starting a drill hole the bit of the drill steel will be held in axial alignment with the rock drill.

Another object is to enable the centralizer to be readily rocked out of the operative position by means of the rock drill after the drilling operation reaches a point in which the guiding function of a centralizer is no longer essential.

Other objects will be in part obvious and in part pointed out hereinafter, and to all of these ends the invention consists of the features of construction and arrangement of parts having the general mode of operation substantially as hereinafter described and claimed and illustrated in the accompanying drawings, in which

25 Figure 1 is a longitudinal side elevation of the front end of a rock drill and its shell showing the manner in which the free end of the drill steel is guided,

30 Figure 2 is an enlarged longitudinal sectional elevation of the centralizer and a portion of the shell taken through Figure 3 on the line 2-2 looking in the direction indicated by the arrows, and

35 Figure 3 is a transverse sectional elevation of the centralizer taken through Figure 1 on the line 3-3 looking in the direction indicated by the arrows.

Referring more particularly to the drawings, A represents a rock drill shell having 40 a conical projection B whereby the shell may be secured to a support for holding the shell in fixed position with respect to a working surface, such as the rock designated by C.

In the drawings only the front end of a 45 front head D is shown for the sake of sim-

plicity of illustration, but it is to be understood that suitable elements, such as guides (not shown) on the rock drill, of which the front head is a part, may interlock with the shell A in a well known manner to enable the 50 rock drill to travel longitudinally of the shell A. A working implement E illustrated as a drill steel extends with its rearward or shank end into the front head D to receive the blows of a hammer piston (not shown) of the drill. 55

In certain drilling operations it is at times a matter of considerable difficulty to maintain the drill bit coaxial with the rock drill, particularly when the rock drill lies in a horizontal position or in positions approaching 60 the horizontal. After a certain period of usage wear is caused in the chuck parts of the rock drill and as a consequence the drill steel tends to incline from the axis of the rock drill. When operating under these 65 conditions the drill bit will swing about the desired axis in starting a new drill hole and as a result the hole may incline from the intended course.

Frequently the foregoing conditions are 70 not detected until a certain depth has been drilled or until drill steels of greater length have been substituted for the starting drill. If then the position of the drill is not changed to coincide with the course of the drill hole 75 the drill steel will bind in the drill hole and will greatly hinder the rotation of the drill steel. As a result of such binding of the drill steel the drilling efficiency will be considerably lowered, the drill bit will require more 80 frequent sharpening and it will also be more difficult to maintain the gauge of the drill bit than would be the case if the drill bit were maintained in axial alignment with the rock drill. 85

The present invention aims to eliminate the foregoing described undesirable features and to this end the rock drill is provided with a centralizer designated generally by F. The centralizer F comprises a yoke G, the 90

arms H of which are suitably spaced to receive the body portion of the drill steel E. Preferably a U-shaped bushing J is disposed in the yoke G to act as a wearing surface for the yoke, so that any wear which may be caused by the drill steel E will be confined to the comparatively inexpensive bushing J and which bushing may be readily and cheaply replaced whenever it becomes unfit for the intended purpose.

In the construction shown the yoke G is provided with an integral stem K having at its lowermost end a transverse portion L in which is formed an aperture O for the reception of a pivot pin P arranged transverse to and off-set with respect to the axis of the drill steel for which the yoke forms a guide so that the said yoke will rock through a plane extending through the axis of the drill steel. The relative proportions of the aperture O and the pivot pin P are preferably such that the yoke G may rock freely on the pin P.

The pivot pin P is seated with its ends into bearing blocks Q arranged on opposite sides of the transverse portion L. The bearing blocks Q therefore lie in the same transverse plane as the stem K and have apertures R through which extend bolts S whereby the bearing blocks Q are secured directly to the front end of the shell A.

If desired, or whenever the centralizer F is applied to certain types of shells, spacers T may be interposed between the bearing blocks Q and the end of the shell to avoid contact between the centralizer and such adjuncts as may protrude beyond the end of the shell, as for instance, a feed screw bearing U which forms a support for a feed screw V whereby the rock drill is actuated longitudinally of the shell. In order to maintain the pin P stationary in the bearing blocks Q pins W are disposed in the bearing blocks Q to extend through the pivot pin P, thus holding said pivot pin P both against rotary and longitudinal movement relatively to the bearing blocks Q.

Suitable means are provided for preventing unauthorized movement of the yoke G out of the operative position. To this end the stem K is provided with an aperture X for the reception of a plunger Y having a flat end Y' adapted to seat on a flat surface Z of the pin P. A spring b is disposed in the aperture X rearwardly of the plunger Y to exert a pressure on said plunger tending to hold it firmly against the flat surface Z. If desired a similar flat surface c may be formed on the forward surface of the pin P to act as a seat for the plunger Y so that when the yoke G is rocked out of the operative or guiding position, said plunger may cooperate with the flat surface c for maintaining the yoke in the inoperative position indicated by dot and dash lines in Figure 1.

In order to assure against movement of the drill steel in the direction of the open end of the yoke G a pin d may be inserted in apertures e in the arms H of the yoke and said apertures e are preferably so located that the pin d may bear lightly against the surface of the drill steel E.

In the operation of the device, whenever it is desired to start a new drill hole the centralizer F may be rocked to the operative position, that is, to a position in which it lies perpendicular to the drill steel E. The pin d may then be inserted in the apertures e to maintain the drill steel E in alignment with the longitudinal axis of the front head D. In this position of the centralizer the plunger Y will bear against the flat surface Z and will be held in engagement therewith by the pressure exerted by the spring b, it being assumed of course that the spring b is capable of exerting a sufficient pressure to hold the centralizer F in this position unaffected by the vibration set up in the rock drill. As the front head D approaches the centralizer F the pin d may be withdrawn from the aperture e and as the drill advances toward the rock C the front head D will strike the centralizer F and will rock it to the inoperative position wherein it will be held by the spring pressed plunger Y.

By means of this invention the front or free end of the drill steel may at all times be held coaxial with the rock drill so that when the bit end of the steel encounters abnormalities in the rock being drilled the steel will be held against departure from the desired course. This is particularly desirable and advantageous in drilling operations wherein it is essential that the holes be drilled parallel to each other, as for instance where the line of cut or drilling is later traversed by a broaching mechanism for removing the material between adjacent drill holes.

I claim:

1. A centralizer for drill steels, comprising a yoke for guiding a drill steel, a stem on the yoke having an aperture, a pair of bearing blocks adapted to be secured directly to the end of a rock drill shell and disposed on opposite sides of the stem, a pin seated fixedly in the bearing blocks and extending through the aperture to form a pivotal support for the yoke, a flat surface on the pin, and a spring pressed plunger in the stem having a flat end to seat on the flat surface for normally holding the yoke against movement with respect to the pin.

2. A centralizer for drill steels, comprising a yoke for guiding a drill steel, a stem on the yoke having an aperture, a pair of bearing blocks secured directly to the end of a rock drill shell and lying in the same transverse plane as the yoke, a pin seated fixedly in the bearing blocks and extending

through the aperture to form a pivotal support for the yoke, a flat surface on the pin, a spring pressed plunger in the stem seating on the flat surface to normally hold the yoke against movement with respect to the pin, a U-shaped bushing in the yoke forming a bearing surface for the drill steel, and a pin insertable in the yoke for maintaining the drill steel coaxial with a rock drill whereby it is actuated.

10 In testimony whereof I have signed this specification.

LEWIS C. BAYLES.
